GAME CABINET

Michael Wichinsky, Hurleyville, N. Y.

Application May 17, 1957, Serial No. 46,214

Term of patent 14 years

(Cl. D34—5)

The single figure is a perspective view of a game cabinet, showing my new design. The opposite side has substantially the same appearance as the side shown, and the back is conventional.

The broken line showing of legible matter is for illustrative purposes only.

I claim:

The ornamental design for a game cabinet, as shown and described.
